FRANCIS J. McCANN, OF EDMONTON, ALBERTA, CANADA, ASSIGNOR TO HEART-
STOOKER COMPANY LIMITED

SHOCK-FORMING MACHINE

Application filed April 24, 1928. Serial No. 272,426.

My invention relates to an improved machine for shocking grain in the field as it is delivered from the harvester and binder, to which said machine is attached.

The main object of my invention is to provide means for receiving the sheaves or bundles as they are ejected from the binder, stacking a number of such sheaves in a bin or receptacle in a substantially horizontal position, and subsequently depositing the sheaves upon the ground, butt ends down, anywhere in the path of the shocker, by tilting the receptacle.

Another object of my invention is to provide means whereby the butt ends of the shocks are spread as the sheaves are deposited on the ground, giving the shocks a greater base area than would otherwise be presented, and thereby insuring self sustainment of the shocks in vertical position.

A further object of my invention is to provide means whereby the shocks, are completely surrounded when the receptacle is tilted and in the depositing position, thereby preventing displacement from the substantial vertical position, due to the centrifugal force of the outermost bundles provided in the tilting of the receptacle.

A still further object of my invention is the novel construction and arrangement of parts which enables the sheaves or bundles to be deposited in shock formation with the least amount of traction effort, thereby reducing the tendency to retard the forward movement of the machine.

Another object is the simple and comparatively inexpensive construction of my machine, which comprises a minimum number of parts operating in a highly efficient manner.

With the foregoing objects and other features which will appear in the following description, taken in conjunction with the accompanying drawings, this invention resides in the combination and arrangements of parts and in details of construction that will be pointed out in the appended claims; it being understood that such changes and variations may be made as fall within the scope of

the claims, without departing from the spirit of the invention.

In the drawings:

Figure 1 is a side elevation of the machine, shown in the normal position.

Fig. 2 is a fragmentary side elevation of the rear portion of the machine, showing the receptacle in the depositing position and parts relative thereto.

Fig. 3 is a view taken at the front of the machine.

Fig. 4 is a rear view.

Fig. 5 is a view substantially on the line 5—5 of Fig. 4.

Fig. 6 is a view substantially on the line 6—6 of Fig. 4, and

Fig. 7 a view substantially on the line 7—7 of Fig. 1.

At the forward end of the machine and carried by the main frame 1 is a trough 2 adapted to receive the bundles or sheaves as they are ejected from the binder, (not shown). The trough 2 has an extended side 4 which acts as a back plate for the bundles, a turned down side 5 permitting the entrance of the bundles from the binder. Extending part way in, and along the base of the trough is an endless chain 6 which passes over sprocket 7, fixed to the shaft 8 that is journaled between the auxiliary frames 9 and 10. The chain 6 travels in the direction indicated by arrows, and passes over the sprocket 11 at the upper end of the inclined trough 12, which is supported by the members 13—13. An idler sprocket 14, aiding in the support of chain 6, is located at the lower end of the inclined trough. Spaced along chain 6 are carrier blocks 15 forming an elevator for service in raising the sheaves within the inclined trough 12.

The chain 6 is driven by the traction wheel 16 which is fixed to the shaft 17, said shaft being journaled in suitable brackets 18 and 19. Fixed to the shaft 17 and lying between the auxiliary frames 9 and 10 is a gear 20, meshing with a gear 21, fixed to the shaft 22, that is suitably supported by journals mounted on the auxiliary frames 9 and 10.

As the sheaves leave the elevator they are deposited on a V-shaped platform 26 that is

supported by members 13'. One side 27 of the platform 26, which is directly under the trough 12 is rigid, while the other side of the platform 28 is yieldable on the pivot 29 against the tension of springs 30 that are arranged to maintain the side 28 in contact with the rigid part 27. During the tilting of the receptacle the side 28 is locked, by means of a swinging bolt 31, secured to the member 28, said bolt passing through a hole 32 in the frame 33. On the frame 33 are secured guides 34-34 for the sliding plate 35 which covers the hole 32, said plate preventing the passage of the bolt 31 when the receptacle is in the tilted position shown in Fig. 2. This plate 35 is operated by means of the crank arm 35' fixed to the rotating pivotal shaft 50 of the receptacle and the link 36. The weight of the sheaves causes the member 28 to swing on the pivot 29, thereby permitting the sheaves to drop into the receptacle 40. The sheaves are carried up the elevator butt ends first and therefore will stack within the receptacle 40 butt ends to the rear.

The tilting of the receptacle is accomplished in the following manner: Fixed to the shaft 17 is a sprocket 37, which by means of a chain 38, drives the sprocket 39 that is freely rotatable on the shaft 40', journaled in suitable bearings 41 and sleeve 42, which is suitably supported by bearing 43 on the main frame 1. The sleeve 42 is slidable upon the shaft 40' and in the bearing 43 and carries a clutch member 44 inside the frame 1 which engages the complementary clutch member 44' carried by the sprocket 39. An annular groove 45 in the clutch member 44 is adapted to receive the pin 46 fastened to the member 47, which serves to move the clutch members 44 and 44' into engagement under control of the operator. Suitable connecting means, (not shown) may be employed in performing this operation. Secured to the sleeve 42, outside the frame 1 is a crank 48 connected to a link 49. A member 48' fixed to the frame 1, lies in the plane of rotation of the crank 48 and serves to automatically disengage the clutch members 44 and 44' at the completion of each cycle. The link 49 is connected as at 51 to a crank 52 formed integral with a gear sector 53, pivoted at 54, and supported by suitable bearings on the main frame 1. Also mounted by suitable bearings on the frame 1 is a shaft 55, to which is fixed the gear 56 meshing with the sector 53. Within the frame 1 and fixed to the shaft 55, is a crank 57, connected to a link 58, which in turn is fastened as at 59 to the base of the receptacle 40.

It will be noted that by the engagement of the clutch members 44 and 44' the receptacle will be tilted about its axis 50 and 50'. The crank 48 pulls link 49 and rotates shaft 55, by reason of the crank 52, sector 53 and gear 56,

the radial ratios of the related parts being such as to cause the cranks 48 and 57 to turn equally. That is: as the crank 48 completes one cycle the crank 57 turns 180 degrees in one direction and returns 180 degrees in the opposite direction to normal position. 76

The radial ratio between the crank 57 and the receptacle 40 due to the arrangement of the relative parts is such as to cause the receptacle 40 to turn one-half so much as the crank 57. That is, when the crank 57 has turned 180 degrees in one direction and returns, the receptacle at that time turns or tilts 90 degrees and returns. 75

In depositing the shock on the ground the rotating movement of the receptacle is likely to upset the vertical stability and cause the rear bundles to fall rearwardly. To overcome this undesirable condition I have caused the member 60 to form a rear wall in order 85 to surround the shock on all four sides when the receptacle is in the depositing position shown in Fig. 2. Without this wall the rear would remain open.

The member 60 is slightly arcuate and is 90 secured to arm 61, pivoted at 62 in suitable bearings 63, supported by the braces 64-64. Secured to the arm 61 is a crank 65 which is connected by the link 66 to the crank 67 on the shaft 68, journaled in suitable bearings, 95 supported by the cross-beam 69. Fixed to the shaft 68 is a crank 70, connected by link 71 to a crank 72 fixed to the pivotal shaft 50' of the receptacle. As shown in Fig. 2, and by the arrangement of the relative parts, 100 the member 60 is in place at the depositing position and is quickly removed on the return to normal of the receptacle so as not to interfere with the shocks as the machine continues its forward travel. 105

In order to spread the butt ends of the shock, the receptacle 40 consists of a bottom 75 having an inclined trough 76 along the longitudinal center thereof as clearly shown in Fig. 4. Arranged along the rear edge of said trough 76 are a series of slightly arcuate members 77, pivoted as at 78, shown in Fig. 6. In the normal position of the receptacle the members are arranged in a transverse vertical plane. The members 77 are capable of 110 swinging 180 degrees. During the tilting of the receptacle the butt ends of the bundles, due to their weight, will tend to swing the members 77 against the action of springs 79 until said members 77 are swung about 90 115 degrees and thereafter they will snap from under the bundles and thereby spread the butt ends. The arrangement of the parts in this action is clearly shown in Fig. 6. The members 77 spread the forward butts of the 120 shock. 125

In order to spread the butts at the sides of the shock, members 80, which are slightly arcuate, are vertically disposed and arranged 130 in a transverse plane and are hinged at 82 to

the rear of the swinging side wall 83', which is hinged at 84 to the end of the stationary side wall 83. During the tilting of the receptacle the side 83' is swung on its pivot 84 through the U shaped bell crank 85 and link 86 connected thereto, said link also connected to the crank 87, fixed on the shaft 55. During the tilting of the receptacle the swinging of the walls 93' take place, thereby spreading the butts along the sides of the shock. During the further tilting of the receptacle the weight of the bundles will tend to swing the members 80 against the action of springs 88 until these members 80 are swung about 90 degrees, and thereafter they snap from under the bundles, thereby aiding the spreading of the butt ends.

Upon the return of the receptacle to the normal position the members 80, now being in the spread or open position will come in contact with abutments 91 which will cause the members 80 to snap back to their normal position.

In order to return the members 77 to their normal position, there are a series of bars 92, connected to one arm of a bell crank 93, the other arm of which is connected as by link 94 to a crank 95 fixed on the shaft 55. Each of the bars 92 is supported at the rear end thereof by a lug 96 arranged under its respective member 77. The bars 92 are arranged to cause the members 77 to snap back to their normal position upon the return of the receptacle. The bars 92 do not interfere with the snap opening of the members as they are quickly withdrawn from the lugs 96 due to the compound action of the crank 55, plus the effect of the offset of bell crank 93 relative to the pivot of the receptacle 50, and conversely the bars 92 do not begin to act on the return to normal of the receptacle until nearly the completion of return of the receptacle.

From the foregoing description it will be seen that I have devised a highly efficient shocker that is capable of forming and depositing the shocks so that they will remain deposited in a vertical position.

Variations within the spirit and scope of my invention are equally comprehended in the foregoing description.

I claim:

1. The combination in a shocking attachment for a harvester binder, of a supporting frame, a substantially horizontally disposed trap-platform carried by said frame, a receptacle arranged directly therebelow, means for conveying the bundles of grain from the binder to the receptacle through the trap-platform, means for maintaining the receptacle in position to receive the bundles, means for tilting the receptacle to deposit the bundles in a shock with their butt ends upon the ground, means for spreading the butt ends of the shock while landing on the ground,

means for completely enclosing the shock on the vertical sides thereof so that the shock remains inert, and means for automatically resetting the parts to their normal position.

2. The combination in a shocking attachment for a harvester binder, of a supporting frame, a substantially horizontally disposed trap-platform carried by said frame, a receptacle arranged directly therebelow, means for conveying the bundles of grain from the binder to the receptacle through the trap-platform, means for maintaining the receptacle in position to receive the bundles, means for tilting the receptacle to deposit the bundles in a shock with their butt ends upon the ground, means for spreading the butt ends of the shock during deposit, means for completely enclosing the shock on the vertical sides thereof so that the shock remains inert, means for locking the trap-platform during the tilting of the receptacle preventing the passage of any bundles therethrough, and means for automatically resetting the parts to their normal position.

3. The combination in a shocking attachment for a harvester binder, of a supporting frame, a receptacle comprising a bottom pivoted to the frame and adapted to swing into substantially horizontal and vertical planes, a pair of vertical sides, each consisting of a stationary part and a swinging part hingedly connected to the rear edge of the stationary part, arranged directly below a substantially horizontally disposed trap-platform, means for maintaining the receptacle in position to receive the bundles, means for tilting the receptacle to deposit the bundles in shock formation directly upon the ground, means for spreading the butt ends of the shock during deposit, means for completely enclosing the shock on the vertical sides thereof so that the shock remains inert, and means for resetting the parts to their normal position.

4. The combination in a shocking attachment for a harvester binder, of a supporting frame having a substantially horizontal trap-platform, a receptacle comprising a bottom pivoted to the frame, a pair of vertical sides, consisting each of a stationary part and a swinging part hingedly connected to the near edges of the stationary part, arranged directly below said trap-platform, means for maintaining the receptacle in position to receive the bundles, means for tilting the receptacle to deposit the bundles in shock formation directly upon the ground, means for spreading the butt ends of the shock during deposit, means for completely enclosing the shock on the vertical sides thereof so that the shock remains inert, means for locking the trap-platform during the tilting of the receptacle, thereby preventing the passage of any bundles therethrough, and means for resetting the parts to their normal position.

5. The combination in a shocking attach-

ment for a harvester binder, of a supporting frame, a receptacle comprising a bottom pivoted to the frame, a pair of vertical sides, each consisting of a stationary part, and a swinging part hingedly connected to the stationary part rearwardly thereof, a series of arcuate end plates hinged to the bottom and swinging side parts extending upwardly and inwardly to partially close the rear side of the receptacle, and arranged to contact with the butt ends of the bundles, means for tilting the receptacle to a substantially vertical position, means for spreading the swinging side parts during the tilting of the receptacle, thereby spreading the butt ends of the bundles, and means for resetting the parts to their normal position.

6. The combination in a shocking attachment for a harvester binder, of a supporting frame, a receptacle comprising a bottom pivoted to the frame, a pair of vertical sides each consisting of a stationary part and a swinging part hingedly connected to the rear of the stationary part, a series of spring held arcuate end plates hinged to the bottom and swinging side parts and extending inwardly and upwardly to partially close the rear side of the receptacle, said end plates being arranged to contact with the butt ends of the bundles, means for tilting the receptacle to a substantially horizontal position, means for spreading the swinging side parts during the tilting of the receptacle thereby spreading the butt ends of the bundles, the spring held end plates being adapted to snap outwardly to completely clear the path of the depositing bundles, and means for resetting the parts to their normal position.

7. The combination in a shocking attachment for a harvester binder, of a support frame, an upwardly inclined conveyor, a substantially horizontal platform to receive sheaves from said conveyor, said platform comprising two sections relatively fixed and yielding, both being inclined downwardly at their adjacent edges, said fixed sections being directly rearward of the conveyor and the yielding section offset to one side thereof, a bolt to retain the yielding section in raised position, means to retract said bolt, a receptacle below said platform to receive sheaves therefrom, said receptacle being pivoted to assume both horizontal and perpendicular positions, means for shifting said receptacle, means for depositing the sheaves from said receptacle directly upon the ground, and means combined with said receptacle to engage and spread the butt ends of the sheaves while passing from the receptacle onto the ground.

Edmonton, April 17th 1928.

FRANCIS J. McCANN.
